UNITED STATES PATENT OFFICE.

FRANKLIN W. OEHRLER, OF PHILADELPHIA, PENNSYLVANIA.

DESIGN FOR A PORTIÈRE-ROPE.

SPECIFICATION forming part of Design No. 26,303, dated November 17, 1896.

Application filed October 10, 1896. Serial No. 608,521. Term of patent 7 years.

To all whom it may concern:

Be it known that I, FRANKLIN W. OEHRLER, a citizen of the United States, residing at Philadelphia, Pennsylvania, have invented and produced a new and useful Design for Portière-Ropes, of which the following is a specification, reference being had to the accompanying drawing, illustrative of the same.

In the accompanying drawing is depicted in side elevation a portière-rope embodying my design.

My invention relates to portière-ropes, a number of which are in practice suspended side by side upon a bracket, curtain pole, or other device, to constitute a portière; such ropes each consisting of a body, such bodies being provided at their upper ends with loops by which they may be mounted upon the curtain pole or supporting device, and at their lower ends with tassels.

The leading characteristics of a portière rope embodying my design are that the rope is formed of a plurality of rope sections of dissimilar appearance, united end to end to form a single continuous portière-rope,—the rope being provided at the points of union of

the several sections with balls or rosette-like structures inclosing and concealing the united ends.

The several dissimilar sections of the portière-rope may be formed all of the same material, having strands, however, which are in one section of color different from the color of the corresponding strand in the adjacent section,—or the dissimilarity in the several sections may be produced by forming the portière-rope of sections of different materials.

In the accompanying drawing the portière rope is formed of three rope-sections, A, B, and C. The loop is designated D, the tassel E, and the frills, balis, or rosettes at the junctions of adjacent sections, are designated F.

What I claim is:

The design for a portière-rope, substantially as herein shown and described.

In testimony that I claim the foregoing as my invention I have hereunto signed my name this 7th day of October, A. D. 1896.

FRANKLIN W. OEHRLER.

In presence of—

ROBERT OSBORNE, Jr.,
ALBERT F. WEBER.
